HENRY F. MERRIAM, OF MAPLEWOOD, NEW JERSEY, ASSIGNOR TO GENERAL CHEMICAL COMPANY, OF NEW YORK, N. Y., A CORPORATION OF NEW YORK.

PROCESS OF MAKING CONTACT SULFURIC ACID.

1,384,566,

Specification of Letters Patent. Patented July 12, 1921.

Application filed October 26, 1920. Serial No. 419,599.

To all whom it may concern:

Be it known that I, HENRY F. MERRIAM, a citizen of the United States, and resident of Maplewood, Essex county, New Jersey, 5 have invented certain new and useful Improvements in Processes of Making Contact Sulfuric Acid, of which the following is a specification.

The new process is carried out in apparatus which is diagrammatically set forth in the drawing. In this drawing 3 represents the sulfur burner. This burner may consist of a Vesuvius burner suitably modified for the burning of sulfur under the conditions hereinafter to be described. In this burner 3 a gas is formed which will, roughly speaking, be approximately an 8% SO_2 gas having a temperature of above 1000° F. For the purpose of this specification the 10 temperature of the gas leaving the burner will be indicated as 1000° F. +. The air required to support combustion in the burner 3 and to form part of the gas therein is preferably dry and to that end the air is 15 first passed through a drying tower 1 and is then conveyed by a Connersville or other positive pressure type of blower or fan 2 into the burner 3. The hot gases from the burner 3 are passed through air cooled pipes 20 constituting the cooler 4 by virtue of which the temperature of the gases is somewhat reduced but is nevertheless conserved at approximately 750° F. under conditions where hazardous condensation of sulfuric acid, 25 when present, is minimized. From cooler 4 the gases still retaining their original heat to the extent of 750° F. enter the converter or contact chamber 5, wherein the mixed SO_2 and air passing over or through platinum contact material is partially converted 30 into SO_3 . Considerable heat is generated in this converter 5 and the gases leaving it have a temperature of approximately 1050° F. The gases, now consisting of SO_3 , SO_2 , 35 and air, pass through a cooler 6 of the same general type and construction as cooler 4 but of sufficient capacity to bring the temperature of the gases down to about 750° F., at which temperature they enter a second 40 converter 7. In the second converter 7 the conversion of SO_2 to SO_3 is practically completed so that as the gases emerge therefrom 45 97-98% conversion has taken place. The temperature of the gases at this point, i. e. 50 where they leave converter 7, is about 830°

F. The cooler 8, similar to cooler 6, reduces the temperature to between 400-500° F., at which temperature the gases are conducted into the absorber 9, of well known construction, and the SO_3 absorbed, the sulfuric acid 60 being continuously withdrawn from said absorber 9 as produced.

It will be observed from the foregoing description that during the entire progress of the gases from the time they leave the sulfur burner 3 to the time that they enter the absorber, their temperature is conserved and maintained, the gas at no point of its travel being reduced in temperature to a point lower than the temperature required for the 70 next operation. In other words, the gases are never at any point permitted to become cool so as to require any substantial artificial reheating to bring them into proper condition for the further treatments. There is, 75 consequently, no countercurrent of the material operated on, which greatly simplifies the structure of the apparatus. The heat changes necessary in this process are all to the end of reducing temperatures and not 80 of raising temperatures. This simplifies construction, etc. The avoidance of radical fluctuations of temperatures means that no work once accomplished requires to be undone and also that no work which is to be 85 done requires intense auxiliary influences. The gases being maintained from the sulfur burner through to the end of the last conversion at temperatures approximating but never materially receding from the temperatures involved in the original creation of the SO_2 gas mixture, it will be apparent that the gas under treatment is, throughout, 90 substantially in the same condition as when formed in the first instance, i. e. there is no great contraction followed by great expansion and no changes of a physical or chemical nature which might be attendant upon such fluctuations of condition as would be 95 represented by sharp contraction of temperature followed by a raising of said temperature. For example, sulfuric acid which might be developed, if any, would at all times be prevented from condensing and the apparatus be, in consequence, preserved 100 against attack.

It has heretofore been considered essential that upon the creation of the SO_2 gas that said gas be purified not only of arsenic but of many other ingredients, such as sulfuric 110

acid in the form of a suspended mist and other sulfural or mercurial impurities. This has been true no matter what material was used as the source of sulfur, and one of the 5 most important discoveries in this art has been that which deals with the necessity of purifying the SO_2 gases so as to prevent them from poisoning the platinum contact material. Even when the practically pure 10 sulfur was used as the source of SO_2 , it has been deemed necessary and essential to purify the gases and particularly to remove therefrom sulfural impurities. The removal of these impurities invariably in- 15 volves a reduction of the temperature of the gases so that the same, after being purified, require a reheating to bring them up to the temperature required for conversion in the contact chambers.

20 I have now discovered that provided the temperature of the SO_2 gases as they leave the sulfur burner are protected against material lowering of their temperature followed by a material raising thereof, satisfactory con- 25 version can be obtained without poisoning the contact material and without destroying the apparatus and with an efficiency equal to that of the standard process but at much less expense provided further that a certain type 30 of sulfur is used in the burner. As illustrative of the type of sulfur which satisfies the conditions, reference is made to Louisiana brimstone and its equivalents, Freeport sulfur or Texas sulfur. This material, al- 35 though containing small percentages of arsenic (As_2O_3) when treated in accordance with the process described and under the conditions of avoiding special purification which the described process implies, does not 40 result in poisoning the contact material in the converters and in some of the tests which were conducted no arsenic was found in the contact material by the most refined methods, although had the full amount of the 45 arsenic present been retained by the contact material, it would have been very easy to detect. The precise reason why Louisiana brimstone, when treated as described, does not result in the poisoning of the contact 50 material, cannot be definitely set down but it may be that the fact is that the percentage of arsenic in the raw material being relatively small is to a large extent retained in the ash without being volatilized, while 55 that proportion which is volatilized, being preserved against reduction of temperature, passes through the contact material in a condition in which it does not injure the same. Perhaps the degree of its dilution may in 60 part account for the failure of the arsenic to act as a material factor in the poisoning of the contact material. Whatever may be the true reason therefor, the fact is that when the source of sulfur is of the Louisiana

brimstone type and the operations are conducted according to the process described, no material poisoning of the contact material takes place. The sulfuric acid mist, also recognized as a contact poison, ceases to be a factor since the temperatures of the gases are throughout kept above the condensing point of sulfuric acid. The sulfur vapor which often acts as a carrier for arsenic seems, under the special conditions of the new process, to either relinquish this function or to exercise it in a manner which is not injurious. The heat of combustion which in prior processes was sacrificed, is now conserved, only so much of it being lost as is needed to reduce the temperatures to those required in the converters. No raising of the temperatures, which is the wasteful part of any operation, is required. By means of this invention the use of the elaborate purifying apparatus heretofore described as necessary when using Louisiana brimstone as the sulfur dioxid source is wholly avoided. Under certain conditions, particularly faulty operation of the burner, it may be advisable to interpose a filtering device in the gas path prior to entry into the converter, to remove mechanical dust.

The practice of the process described may, of course, within reasonable limits, be modified by occasional reduction of temperature at various points, such temperature losses being substantially compensated for by proper heat addition, and in my claims I intend to cover such variants of the process described, it being understood that when I speak of maintaining the temperature or of preventing the temperature from falling below certain limits, I mean to exclude that kind of temperature diminution which is characteristic of the purification processes now generally employed. So long as a substantial and material amount of the original heat of the gases (*i. e.* a heat approximating or, at least, not greatly deviating from the temperature required for catalysis) is conserved and carried through until 97-98% conversion is achieved, the process falls within the intended scope of my claims.

I claim:

1. The improvement in the method of making sulfuric anhydrid by the contact process, which comprises employing as the raw material for the production of sulfur dioxid, sulfur in the form of brimstone of the Louisiana brimstone type, burning the same to produce gas containing sulfur dioxid and oxygen and conducting said gas over catalytic material until approximately 97-98% conversion has taken place and then absorbing the anhydrid formed, the entire operation from the burning of the gas to the end of the conversion stage being conducted without permitting the temperature of the gas

to fall materially below the temperature required for the production of sulfuric anhydrid in the converter.

2. The improvement in the method of
5 making sulfuric anhydrid by the contact
process, which comprises employing as the
raw material for the production of sulfur
dioxide, sulfur in the form of brimstone of
the Louisiana brimstone type, burning the
10 same to produce gas containing sulfur di-
oxide and oxygen and conducting said gas to
platinum contact material while maintain-
ing a temperature in said gas above 700° F.
3. The improvement in the method of
15 making sulfuric anhydrid by the contact

process which comprises employing as the
raw material for the production of sulfur
dioxide, sulfur in the form of brimstone of
the Louisiana brimstone type, burning the
10 same with dried air to produce a gas con- 20
taining sulfur dioxide to the extent of eight
per cent. by volume and oxygen and con-
ducting said gas to platinum contact mate-
rial without permitting the temperature
thereof to fall materially below the tem- 25
perature required for the production of sul-
furic anhydrid in the converter.

In testimony whereof I have hereunto set
my hand.

HENRY F. MERRIAM.
